UNITED STATES PATENT OFFICE

170,637

RAILWAY CAR BODY

Ralph W. Haman, Flossmoor, and Clarence V. Norby, Chicago, Ill., assignors to Pullman-Standard Car Manufacturing Company, Chicago, Ill., a corporation of Delaware

Application April 12, 1952, Serial No. 19,302

Term of patent 14 years

(Cl. D66—1)

To all whom it may concern:

Be it known that we, Ralph W. Haman and Clarence V. Norby, citizens of the United States of America, and residents, respectively, of Flossmoor, county of Cook, and State of Illinois, and Chicago, county of Cook, and State of Illinois, have invented a new, original, and ornamental Design for Railway Car Body, of which the following is a specification, reference being had to the accompanying drawings forming part thereof.

In the drawings—

Fig. 1 is a general perspective view of a conventional railway car body in which our new design is incorporated, having portions broken away better to reveal the disposition of the cocktail dining room within the vehicle and showing the supporting trucks in dotted lines for illustrative purposes only;

Fig. 2 is a horizontal mid-sectional view taken through the vehicle showing the cocktail dining room in plan;

Fig. 3 is a vertical longitudinal sectional view through the vehicle showing a side elevation of one side of the cocktail dining room taken on line 3—3 of Fig. 2;

Fig. 4 also is a vertical longitudinal sectional view through the vehicle showing a side elevational view of the other side of the cocktail dining room taken on the line 4—4 of Fig. 2;

Fig. 5 is a vertical transverse sectional view

through the vehicle showing an elevational view of one end of the cocktail dining room taken on the line 5—5 of Fig. 2;

Fig. 6 also is a vertical transverse sectional view through the vehicle showing an elevational view of the other end of the cocktail dining room taken on the line 6—6 of Fig. 2;

Fig. 7 is a general perspective view of one end of the cocktail dining room in the railway car body; and

Fig. 8 is a general perspective view of the other end of the cocktail dining room.

The characteristic features of the present design reside in the interior cocktail dining room design shown in the drawings.

The dominant features of the design reside in those portions shown in full lines.

What is claimed is:

The ornamental design for a railway car body, substantially as shown and described.

RALPH W. HAMAN.
CLARENCE V. NORBY.
